(57) **CLAIM**

The ornamental design for a wrench and socket holder, as shown and described.

DESCRIPTION

FIG. 1 is a perspective view of the wrench and socket holder showing my new design;

FIG. 2 is an end elevational view taken from the upper end of FIG. 3;

FIG. 3 is a top view thereof;

FIG. 4 is a right side elevational view thereof, the left elevational view being a mirror image;

FIG. 5 is a bottom plan view thereof; and,

FIG. 6 is an end elevational view taken from the lower end of FIG. 3.
